UNITED STATES PATENT OFFICE.

JAMES E. HUNT, OF ST. JOSEPH, MISSOURI.

DESIGN FOR A BOOTH.

Application filed October 5, 1928. Serial No. 28,374. Term of patent 14 years.

To all whom it may concern:

Be it known that I, JAMES E. HUNT, a citizen of the United States, residing at St. Joseph, in the county of Buchanan and State of Missouri, have invented a new, original, and ornamental Design for a Booth, of which the following is a specification, reference being had to the accompanying drawing, forming part thereof, and in which—

Fig. 1 is a plan view; and Fig. 2 is an elevation of a booth showing my new design.

I claim:

The ornamental design for a booth, as shown.

JAMES E. HUNT.
